UNITED STATES PATENT OFFICE

111,493

DESIGN FOR A FINGER RING OR SIMILAR ARTICLE

Joseph L. Herzog, New York, N. Y.

Application June 7, 1938, Serial No. 77,643

Term of patent 14 years

To all whom it may concern:

Be it known that I, Joseph L. Herzog, a citizen of the United States, residing at New York, in the county and State of New York, have invented a new, original, and ornamental Design for a Finger Ring or Similar Article, of which the following is a specification, reference being had to the accompanying drawing, forming a part thereof.

In the drawing, Figure 1 is an edge view on an enlarged scale of a finger ring embodying the new design.

Figure 2 is a fragmentary view on a further enlarged scale of a portion of the edge of the ring.

Figure 3 is a side view of the ring on the enlarged scale of Figure 1; the ornamentation shown in full lines extends throughout the entire circumference of the ring.

The stippled and unstippled portions of the ring, best shown in Figs. 1 and 2, represent metals of contrasting color.

I claim:

The ornamental design for a finger ring or similar article, substantially as shown and described.

JOSEPH L. HERZOG.
